UNITED STATES PATENT OFFICE

91,317

DESIGN FOR A JUG

William Brown Cleland, Hamilton, Ontario,
Canada, assignor to Jordan Wine Company,
Ltd., Jordan, Ontario, Canada, a corporation of Canada

Application October 30, 1933. Serial No. 49,595

Term of patent 14 years

To all whom it may concern:

Be it known that I, WILLIAM BROWN CLELAND, a citizen of the Dominion of Canada, residing at Hamilton, in the county of Wentworth, Province of Ontario, Canada, have invented a new, original, and ornamental Design for a Jug, of which the following is a specification, reference being had to the accompanying drawing, forming part thereof.

I claim:

The ornamental design for a jug, as shown.

WILLIAM BROWN CLELAND.
